UNITED STATES PATENT OFFICE.

JONATHAN A. HUNT, OF SALEM, MASSACHUSETTS, ASSIGNOR TO FREDERICK L. EMERY, OF LEXINGTON, MASSACHUSETTS.

ROD-GRINDING MACHINE.

Application filed August 17, 1920. Serial No. 404,111.

To all whom it may concern:

Be it known that I, JONATHAN A. HUNT, a citizen of the United States, and a resident of Salem, in the county of Essex and State 5 of Massachusetts, have invented an Improvement in Rod-Grinding Machines, of which the following description, in connection with the accompanying drawings, is a specification, like characters on the drawings representing like parts.

This invention relates to machines for pointing wires or rods and especially for separating wires or rods from a mass and advancing them to the pointing instrumentalities. An object of the invention is to provide means for separating the rods from the mass and in advancing them in proper parallel relation so as to prevent tangling or twisting thereof and to insure the feeding of said rods in single layer formation.

The invention will be best understood by referring to the following specification taken in connection with the accompanying drawings of one specific embodiment thereof.

In the drawings—

Fig. 1 is a front elevation of the upper portion of the machine embodying this invention;

Fig. 2 is a detail vertical section taken on the line 2—2 of Fig. 1;

Fig. 3 is a longitudinal section through the wire and rod separating and advancing means taken substantially on the line 3—3 of Fig. 2;

Fig. 4 is a horizontal detail section through one side of the rod separating and feeding means taken on the line 4—4 of Fig. 3; and

Fig. 5 is a vertical section taken substantially on the line 5—5 of Fig. 2 at the left hand end of the rod mass container.

In the drawings a frame 1 is shown whereon the various instrumentalities of the machine are supported. This frame may be of any appropriate shape or design but herein is of substantially box-like construction.

Mounted within said frame is a casing or housing 2 adapted to contain the work-forming member herein an abrasive grinding wheel 3, the latter being secured to an arbor 4 journalled in bearing boxes 5 at oppo-

site sides of said grinder housing 2. The grinding wheel 3 is provided with a concave grinding face 6.

The grinder or work-forming member 3 55 may receive its power from any appropriate source not shown.

The housing 2 for the grinder surrounds the greater portion of the periphery thereof so as to catch the grinding dust discharged 60 from said grinder. Suitable means may be provided for taking care of said dust, the latter being omitted from the present drawing.

In machines of the character embodying 65 this invention the work is fed transversely of the face of the grinding wheel or work-forming member and preferably in a substantially tangential relation thereto but at an angle to the axis of the grinder, the 70 grinding operation being initiated at the end of the work at a point in the circumference in advance of the point of contact of the tangent with its circle, the end of the work being moved during the feeding operation at 75 an angle to but toward a radial plane passing through said point of contact. As the work, herein rods or wires, is advanced transversely of the grinding face of the wheel, its ends will gradually assume the 80 form of a point by reason of the gradual approach of the work to said plane.

It is obviously within the scope and purpose of the invention to form either a chisel or round point upon the ends of the rods 85 but in the present example means for feeding the work so as to effect the rounding of the points are shown, said means preferably including a plurality of saddles 8 and cooperating feed wheels 9. The saddles 8 have 90 arcuate resilient guiding surfaces 10 substantially coinciding with the concave face 6 of the grinding wheel. The cooperating faces of the feed wheels are likewise resiliently surfaced as at 11 to conform with the 95 faces or surfaces 10 of said saddles.

It is desirable, at times, to vary the angle of approach of the rods or work with respect to the grinding surface of the member 3 so that the taper or angle of the finished point 100 may be long or short and in the present example this adjustment is provided for by

mounting the saddles 8 and their cooperating feed wheels 9 upon a suitable work table 12 to which lateral, longitudinal or transverse movement may be imparted to vary its 5 relation to the work member as will herein-after be described.

The table 12 has an opening 13 through which the housing and grinding wheel are adapted to protrude in order that the work 10 carried by the table or saddles may be brought into contact with the grinding face of said grinding wheel. The work table 12 is inclined at an angle to a horizontal plane inclining downwardly toward the left in 15 Fig. 1 and said table is preferably mounted so that this angle may be varied from time to time as needs require. The saddles 8 are mounted upon the table 12 within the opening 13 (see Fig. 2).

20 There are occasions when a fine adjustment of the table relative to said grinding wheel is desirable. Therefore appropriate means for effecting such an adjustment are provided, the present example including an 25 adjusting screw 14 (see Fig. 1) arranged in screw-threaded engagement with a bracket 15 and with its inner end engaging the edge of a plate 16 on which rests the left or lowermost end of the table 12.

30 The bracket 15 has ears 17 through which passes a shaft 18, the latter being supported in suitable bearings 19 on the frame 1. The shaft 18 is provided with cams or eccentrics 20 arranged to engage the plate 16 and an 35 operating lever 21 is attached to one end of said shaft whereby said shaft may be rotated or rocked when it is desired to raise the end of said work table and remove the ends of said rods that are being pointed 40 from contact with the grinding wheel.

The right-hand end of the table 12, as viewed from Fig. 1, is also adjustable vertically, herein by means of screw-threaded rods 22 pivotally attached at 23 to the under 45 side of said table, the lower ends of said screws engaging the plates 24 wherein they are held in their adjusted position by check nuts 25. The plates 24 are also slotted as shown at 26 to receive the screws 27 which 50 extend through said slots and into screw-threaded engagement with brackets 28 attached to opposite corners of the frame 1, thus allowing a limited adjustment of said plates without removing the screws 27.

55 From the foregoing it will be seen that universal adjustment of the table 12 is possible.

In machines of the type shown, considerable difficulty has heretofore been experienced in feeding rods to the grinding wheel by reason of the fact that rods of considerable length become twisted about each other and thus clog the feeding devices of the machine but in the present machine this has 60 been overcome by providing a plurality of 65

sets of feed members each including a saddle and feeding wheel, each set being adjustable to positions best suited for feeding certain lengths of rods.

The feed wheels 9 are mounted upon a 70 suitable shaft 29 journaled to rotate in suitable bearings such as boxes 30 vertically adjustable in appropriate standards or brackets 31 carried by the table 12. The wheels 9 are preferably keyed to said shaft but are 75 capable of movement longitudinally thereof. The shaft 29 receives its motion from any suitable source through a counter-shaft 32, the latter having a pulley 33 secured thereto and driven by a belt 34 arranged so that 80 upon a slight upward tilt of the table 12 by the cams 20, said belt will be a slackened sufficient to prevent further movement of said shaft, thus stopping the feed of the rods to the grinding wheel. 85

Means are also shown herein for adjusting the feed wheels 9 toward or away from the grinding surfaces of the saddles 8 to accommodate for variations in size of different lots of work and preferably it is desirable 90 that the two or plurality of feed wheels be given simultaneous and uniform movements so that the same amount of pressure will always be brought to bear upon all portions of the rods, thus insuring an equal feeding 95 movement of both ends of the rods. For this purpose means are provided comprising screws 35 shown in dotted lines in Fig. 1, one being rotatable in each of the standards 31 and having screw-threaded engagement 100 with the boxes 30. The screws 35 are provided with bevelled gears 36 to mesh with bevelled gears 37 fast to a common operating shaft 38 arranged to rotate in suitable bearings in said standards. A hand wheel 39 is 105 attached to the shaft and serves as means for manually operating the same to raise and lower said boxes.

It is desirable that the rods or work be fed by said feed wheels in a single layer, 110 transverse of the face of the grinding wheel, in order that each rod shall receive the same amount of grinding and that the grinding be uniform all around so as to bring the point as nearly as possible at the 115 center of the rod. It is also desirable that the machine be automatic; that is that the rods be fed or separated from a mass and advanced or delivered to the feeding means in a single layer formation. Therefore in 120 the present example means are provided for containing a mass of rods, said means consisting of a chute-like member 40 mounted upon the table 12 and including side members 41 and 42 and a bottom 43. The bottom 43 is preferably pivoted between the side members 41 and 42 at 44 and means are provided as at 45 for securing said bottom in predetermined angular positions. The inner edge of said bottom 43 is ar- 125

ranged substantially parallel with the table 12 and the rods in the mass will incline equally when placed upon said bottom and by reason of the inclination downward toward the grinding wheel; hence said rods will have a tendency to slide toward the lower end of said container and thus even said ends preparatory to their being advanced to the grinder. The bottom 43 also inclines downwardly from the receiving end at 46 toward the grinding wheel, this inclination being most clearly shown in Fig. 2 and adjacent to the inner or lower end of said bottom I have provided rod separating or feeding means 47 which, in the present example, consists of a cylindrical drum 48 provided with peripheral spaced projections 49 herein consisting of forwardly inclined blades 50 extending longitudinally of said drum and projecting a predetermined distance from the face thereof, said blades being separated from each other herein a distance sufficient to take in approximately three wires or rods, although clearly within the spirit and scope of the invention this distance may be varied as desired.

The drum 48 is herein shown mounted upon a shaft 51 journalled to rotate in appropriate bearings as at 52, 52 secured to the side members 41 and 42. The drum 48 is so arranged within the container 40 and in relation to the forward or lower end of the bottom 43 that said blades 49 will pass upwardly in the direction of the arrow α during the rotation of said drum, in close proximity to said lower edge of the bottom 43, in fact so close that any rods which happen to be at said edge and within the path of the projecting portions of said plates will be picked up thereby and carried to the top of said drum, whence they are guided by suitable means hereinafter described to the receiving ends of the saddles 8. The point in the periphery of the drum 48 where the rods or wires leave said drum is approximately on a level with the receiving ends of the saddles 8 and there is, in the present example, a slight gap between said highest point of the drum and said receiving ends of the saddles and across this gap means are provided such as a guide plate 53 for guiding the work from said drum to said saddles. The upper surface of said plate is arranged substantially with the face of said drum so as to form a continuation of the surface of said drum, and in order to insure the following of the work of rods along said plate rather than around the drum beyond said highest point, means are provided herein consisting of stripping fingers 54 arranged in suitable recesses 55 formed in the face of said drum so as to bring the outer edges of said fingers substantially flush, except as hereinafter

stated, with the face of said drum and thus serve as guiding means to transfer said rods or work from the drum to the guide plate 53. In order to provide gaps or recesses for said stripping fingers in the present example, the drum 48, instead of being made in one piece, is made in separate sections 56 (see Fig. 3), each section being attached to the shaft 51 as shown in section in said Fig. 3. The stripping fingers 54 are arranged to extend along said recesses part way around the face of the drum from the forward edge 57 of said guide plate 53 and terminate in partially rounded ends 59, said stripping fingers projecting beneath said guide plate and being secured to the under edge thereof herein by screws 58.

Obviously the diameter of the wires that are to be pointed by the machine may vary and therefore the projection of the blades beyond the periphery of the drum should desirably be great enough to accommodate the largest size of wire or rod that a machine is capacitated to operate upon, but it is desirable that the projection of said blades, particularly at the point in the circumference of the periphery of the drum near the outer edge 57 of said guide plate, be at least no greater than the diameter of the wires or rods that are being advanced thereby so that said rods will be maintained, as they are advanced along the upper surface of said guide plate, in single layer formation. Therefore to produce the desired amount of projection, the forward edge 57 of said guide plate and the stripping fingers attached thereto are arranged adjustably, preferably in the following manner:

The plate 53 is supported at its inner edge by lugs 84 projecting inwardly from the side members 41 and 42 and screws 85 projecting through said plate and through said lugs maintain said table in the desired relation thereto but permit a slight raising and lowering of the outer edge 57 thereof, which raising and lowering movements are effected by means of adjusting screws 86 extending through said side members and in contact with the underside of said plate near said forward edge. Thus by rotating the screws 86 said plate 53 will be tilted upon the lugs and the fingers 54 will in consequence be raised or lowered to vary the projection of the blades beyond the outer edges 87 of said fingers. As previously stated, the fingers 54 extend only part way around that portion of the periphery of the drum that is within the rod mass container.

It is equally desirable to provide means for regulating the projection of the blades 50 near the bottom of the container so that more than one layer of rods will not be

picked up thereby as said blades pass through the mass, particularly in cases where the normal projection of said blades beyond the periphery of the drum, is 5 greater than the diameter of the rod that is being handled by the machine. In the present example means are provided for regulating the projection aforesaid consisting of a second series of fingers 88 which 10 series is secured to a bar 89 extending lengthwise of the rod mass container between the side members 41 and 42. This bar is mounted upon an appropriate plate 90 secured to the side members 41 and 42 15 and extending longitudinally of said rod mass container and is arranged on said plate to move toward and away from the axis of the drum and herein adjusting screws 91 and stop screws 92 carried by said plate, are arranged to effect a fine adjustment and positioning of said bar in the direction mentioned.

Screws 93 project through slots 93^a in said plate and into engagement with said bar and positively hold said bar in its adjusted position. From the foregoing description it will be seen that a fine adjustment of the fingers 88 may be effected to provide for the exact amount of projection of the blades 50 beyond the outer curved faces of said fingers.

The fingers 88 are arranged at their lower ends to extend into recesses or suitable notches 94 formed in the inner edge of the 35 bottom 43 (see Fig. 4), thus insuring, at all times, the closing of the gap between said fingers and said bottom to prevent small rods or wires from passing downwardly therethrough due to the adjustment aforesaid. From this arrangement it will be 40 seen that a pocket 61 will be formed at the very bottom of the rod mass container of such a shape that even though the mass of rods as shown at b, Fig. 2, is very small 45 it will be crowded against the face of the guide fingers 88 and the corresponding face of the rotary member 48 so that as the blades 50 travel upwardly between the stripping fingers, they will pick up a limited 50 number of the rods and carry them upwardly along the outer curved edges of said fingers and when they reach the uppermost point in the drum, said rods will be stripped or removed from in front of said 55 blades and advanced in single layer formation along the upper guiding surface of the plate 53 to said saddles.

To prevent more than one layer of rods or wires from being carried by the blades 60 of the conveyor or drum to the plate 53 a wiper 62 is provided herein consisting of a strip of resilient material such as felt 63 mounted upon a bar 64, said felt and said bar extending substantially the length of 65 said rod mass container. The bar 64 is

suspended by means of hangers 65 from a shaft 66, said shaft being arranged to rock in appropriate bearings 67 in the side members of said rod mass container. An operating arm 68 is attached to said shaft and affords means for rocking the same so as to remove the wiper from contact with the rods, the normal operating position of said wiper being shown in Fig. 2. Said wiper is herein adapted to wipe off all superfluous rods which chance to stick to the periphery of the drum and are carried along thereby toward the feeding means.

It is equally desirable to prevent piling up of the rods as they are pushed by the blades of the drum along the top of the plate 53 toward the feeding means including the feed wheels 9 and saddles 8. For this purpose I provide a row of fingers 69 preferably placed directly above the stripping fingers 54 and means are herein provided to space said fingers 79 from the fingers 54 a distance substantially equal to the diameter of the rods or wires that are being advanced along said guide plate, said means being such as to provide adjustment to accommodate rods of various diameters and also to permit said fingers to be raised when said rods become stuck for one reason or another in their passage to the feeding members. The means herein provided for the purpose specified include bars 70 and 71 arranged between the sides 41 and 42 and supported, at their opposite ends, by hangers 72, 73 (see Figs. 2 and 3). The hangers 72 and 73 have portions 74 which lie against the inner faces of the members 41 and 42 to which portions the ends of the bars 70 and 71 are attached. The hangers 72, 73 are pivotally supported at opposite ends of a shaft 75, the latter having eccentric cams 76, 77 secured to opposite ends thereof and encircled by eccentric straps 78, the latter secured by screws 79 to the side members 41 and 42. A handle or operating member 79 is attached to one of said cams and serves as means for rocking said shaft with the cams thereon to raise and lower the bars 70 and 71 and the fingers attached thereto.

It is desirable that the opposite ends of the fingers 69 be positioned at exactly the right distance from the upper surface of the guide plate 53 and so that the pressure of said fingers upon the rods which are being rolled or advanced along said guide plate will be the same all along the row of rods; that is from the forward ends to the rear ends of said fingers. To effect this result means are provided herein consisting of stop screws 80 and 81 which are arranged in a flange 82 projecting from the hangers 72, 73 outwardly over the top edge of the side members 41, 42, said set screws being held in their adjusted positions by check nuts 83,

said screws being set one over each of the bars 70 and 71 and in such positions as to maintain the flange 82 at predetermined distances from said side members, thus limiting the downward movements of said hangers and likewise the fingers 69.

The present machine is capable of handling either long or short rods but when short rods are being separated from the mass it is desirable that the fingers 54 and 69, as well as the fingers 88, be placed nearer together in order to prevent the short ends from dropping down and getting caught during the feeding operation. For this reason the fingers near the lower end of the drum, or the right end in Fig. 3, are placed quite close together, the spacing thereof gradually increasing toward the upper end of said drum, at which end said fingers are much more widely separated than at the lower end as will be seen by referring to Fig. 3.

Very often the mass of rods within the container are not positioned so that the ends thereof which are to be ground properly align, although the inclination of the bottom 43 of said container downwardly toward the left in Fig. 1, has a tendency to even the ends of said rods against the lower end of said container. Therefore to facilitate the evening of said ends, said container is provided with an evening plate or guide member 95. This guide member has a portion 96 that is inclined slightly (see Fig. 4) so that as said rods work down the inclined bottom 43 toward the drum, they will be crowded longitudinally of the container toward the upper end thereof until they reach a straight portion 97 which finally guides them to the saddles and feed wheels cooperating therewith.

In addition to being inclined as shown at 96 the guide member or evening plate is also inclined with respect to a vertical plane as shown in Fig. 3. Thus as said rods are being elevated by the blades 50 of the conveyor or drum, the latter inclination will, by cooperating with the inclination 96, effect the proper evening of said rods before they reach the upper surface of the guide plate 53 where further endwise movement thereof will be prevented owing to the pressure of the fingers 69 thereon.

In addition to the provision hereinbefore described for varying the projection of the blades beyond the stripping fingers 54, means are provided for effecting similar results which involves the adjusting of the shaft 51 bodily together with the drum thereon up or down as desired and for this purpose the bearings 52 extend through enlarged openings 98 formed in the side members 41 and 42 and the bearings 52 are also provided with lugs 99 projecting from opposite sides thereof as shown in dotted lines

in Fig. 2 and through these lugs are adjusting screws 100 which engage the upper face of the table 12 and upon movement of said screws, said bearings will be raised or lowered as desired and thus effect a result similar to the raising and lowering of the stripping fingers 54.

Various methods may be employed for revolving the drum 48 but herein I have preferably provided means operative from the shaft 29 whereby said conveyor means will operate only when said shaft operates and thereby prevent the piling up of the work in front of the feed wheels 9 should said feed wheels be stopped for any reason.

In the present example I provide means for driving said conveyor mechanism including a friction clutch 101 attached to one end of the shaft 29 as shown most clearly in Fig. 1 and having manually operable means 102 for throwing said clutch out of operation if, for any reason, it is desired to stop the feeding of rods to the feed wheel without discontinuing the movements of said feed wheels. The clutch may be and herein is of well known construction and needs no further description. This clutch is arranged to cooperate with a sprocket 103 normally loose upon the shaft 29, said sprocket being operatively connected by means of a chain 104 with an idler sprocket 105 shown in dotted lines in Fig. 2 adjustably mounted upon the side member or frame 41.

In passing to said idler sprocket one run of said chain, preferably the lower run thereof, is arranged to engage the teeth of a sprocket gear 106 attached to the end of the shaft 51, thus causing said shaft 51 to be rotated in a reverse direction to that of said feed wheels 9. As previously described the sprocket 105 is adjustably mounted in the side frames 41 and this adjustment, taken in connection with the adjustment for the bearings of the shaft 51, namely the screws 100, permits of proper adjustment of the said sprockets to compensate for any variation in the length of the chain due to the adjustment of one or the other of said sprockets.

In the foregoing description the words "wires" and "rods" have been used in describing the work and it is distinctly to be understood that neither word is used in a limiting sense but that the machine is capable of operating upon work which may reasonably fall within the scope of either of said words, the present machine being capable of handling rods or wires of different diameters. Furthermore either round, hexagonal, square or numerous other polygonal shapes of rods or wires may be handled by said machine; also short, medium or long rods.

While I have herein shown and described merely for illustrative purposes a specific

embodiment of my invention and have disclosed and discussed in detail the construction and arrangement incidental to such disclosure, it is distinctly to be understood that 5 the invention is limited neither to the mere details or relative arrangement of parts nor to the specific application herein shown but extensive variations from the illustrations may be made without departing from the 10 principles thereof.

Claims.

1. In combination, a grinder and means to feed work elements to said grinder including spaced guide fingers, the spaces between 15 said fingers gradually decreasing toward the work ends of said work elements.

2. In a grinding apparatus, a rotary feed member provided with interrupted longitudinal teeth and guide fingers arranged in 20 the interruptions in said teeth adapted to determine the amount of projection of said teeth and to strip the work from said teeth at a selected point.

3. In combination, a grinder, means to 25 feed work to said grinder, a rotary member provided with peripheral projections adapted to separate the work from a mass and advance the same to said work feeding means, two cooperating sets of fingers respectively to vary the amount of projection 30 of said peripheral projections into the work mass and to strip the work from said peripheral projections, said fingers being arranged to guide the work to said work feeding means, and means to maintain the work in single layer formation until it reaches 35 said work feeding means.

4. In combination, a grinder and means to 40 separate work from a mass and advance the same to said grinder, said means including a rotary member having spaced peripheral blades, strippers disposed at intervals longitudinally of said rotary member to strip the work from said blades, and means to maintain said work in single layer formation.

5. In combination, a grinder and means to 45 advance work elements in single layer formation to said grinder, said means including spaced guide fingers, the spaces between said fingers being least near the ends of the rods where the grinding is to take place.

6. In a rod or wire pointing machine, means to arrange said rods in single layer formation for pointing including a rotary member having peripheral projections and guide fingers for said rods to cooperate with said projections, and means to effect a positive adjustment of said guide fingers relative to said projections to compensate for 50 variations in the diameter of the work.

7. In combination, a grinder, a rotary 55 drum having longitudinally disposed peripheral projections to engage and advance rods toward said grinder, and stripping fingers arranged at separated points along

said drum to strip the rods from said projections and guide them toward said grinder, and means to maintain said rods in single layer formation on said stripping fingers.

8. In combination, a work forming member, means to guide rods in single layer formation to said work-forming member including a guide plate, a series of spaced guide fingers, means to raise and lower said guide fingers relatively to said plate, and means to effect a separation between said plate and said fingers corresponding to the size of the work to be guided therebetween. 70

9. In combination, a work forming member, means to guide rods in single layer 80 formation to said work forming member including a guide plate, a series of spaced guide fingers to cooperate with said guide plate, means to advance rods between said guide plate and said fingers including a rotary member provided with longitudinal peripheral ribs, and means to vary the position of said rotary member relatively to 85 said guide plate.

10. In combination, a work forming member, means to advance work toward said work forming member including a plurality of toothed rotary members arranged to rotate as a unit, the continuity of the teeth of said plurality of rotary members being 90 interrupted at a plurality of points, and means arranged within said interruptions in adjustable relation to the peripheries of said rotary members, adapted to vary the effective portions of the teeth of said rotary members and to strip the work from said teeth. 95

11. In combination, a work forming member, means to advance work toward said work forming member including a plurality of spaced rotary members arranged to rotate as a unit, said rotary members having peripheral projections adapted to cooperate to advance all portions of the work uniformly, and stripping fingers arranged in the spaces between said rotary members. 100

12. In combination, a work forming member, a plurality of spaced rotary members arranged to rotate as a unit, said members having spaced peripheral projections adapted to cooperate to engage and uniformly advance all portions of the work toward said work forming member, and fingers arranged to occupy the spaces between said rotary members and to strip the work carried thereby from said projections at a determined point in the rotation of said members. 115

13. In combination, a work forming member, means to guide rods in single layer formation to said work forming member including a guide plate, guide fingers spaced from said guide plate a distance substantially coinciding with the diameter of the 120 125 130

work, said guide fingers being arranged to cooperate with said guide plate to maintain the work in single layer formation while upon said guide plate, and means to roll 5 said work along said guide plate.

14. In combination, a work forming member, means to guide rods in single layer formation to said work forming member including a guide plate, guide fingers spaced 10 from said guide plate a distance substantially coinciding with the diameter of the work, said guide fingers being arranged to cooperate with said guide plate to maintain the work in single layer formation 15 while upon said guide plate, means to vary the normal space between said guide fingers and said guide plate to correspond with variations in the work, and means bodily to remove said guide fingers from their 20 normal positions relative to said guide plate.

15. In a machine of the character described, a toothed feed member, means to guide the work to said feed member, including a downwardly inclined plate, spaced 25 guide fingers arranged adjacent to the edge of said plate and adapted to cooperate with said feed member to separate and advance the work, and means to vary the extent of 30 projection of the teeth of said feed member beyond the working edges of said guide fingers to correspond with the diameter of the work.

16. In a machine of the character described, a toothed feed member, means to guide the work to said feed member, including a downwardly inclined plate, spaced 35 guide fingers arranged in recesses in the edge of said plate and adapted to cooperate with said feed member to separate work 40 from a mass, and means to adjust said guide fingers laterally of the edge of said plate to vary the extent of projection of the teeth of said feed member beyond the working 45 edges of said guide fingers.

17. In combination, a work forming member, a work container, a rotary drum having forwardly inclined blades inserted in its periphery to separate work from the mass 50 and advance the same toward said work forming member, and means to vary the amount of projection of said blades to correspond with the size of the work.

18. In combination, a work forming member, a work container, a rotary drum provided with radially projecting blades for separating the work from the mass in said container and advancing it toward said work forming member, guide fingers arranged in 55 grooves in said drum to regulate the extent of projection of said blades to correspond with the diameter of the work; means to strip the work from said blades, and means to guide said work to said work forming 60 member.

19. In combination, a work forming member, means to feed the work in single layer formation to said work forming member, and means frictionally driven from said work feeding means to separate work from 70 a mass and arrange it in single layer formation preparatory to being fed.

20. In combination, a grinder, means to feed work to said grinder including a plurality of feed wheels arranged simultaneously to engage the work, means for removing the work from contact with said grinder and for simultaneously rendering said feeding means inoperative, means to separate the work from a mass and arrange the same in 80 single layer formation for feeding, and frictional means operatively connecting said separating means with said feed means to permit said separating means to stop when work has become caught therein.

21. In combination, a work member, and means including a bladed rotary drum for separating the work and advancing the same 85 in single layer formation toward said work member.

22. In combination, a work member, means for feeding work to said work member including a rotary member provided with peripheral projections adapted to separate the work from a mass and advance the same to said work members, fingers disposed at predetermined points in the length of said rotary member to strip the work from said peripheral projections, and a second set of fingers extending from the vicinity of the work mass into abutting relation to the stripping fingers, said second set of fingers being adjustable relatively to the extremities of said peripheral projections to vary 100 the effective area of said projections.

23. In combination, a work member, means for feeding work to said work member including a rotary member provided with peripheral projections adapted to separate the work from a mass and advance the same to 105 said work member, and two sets of independently adjustable fingers adapted respectively to regulate the effective area of said projections in the vicinity of said work mass and to strip the work from said peripheral projections.

24. In combination, a work forming member, means to guide rods in single layer formation to said work forming member, guide fingers spaced from said guide plate a distance substantially coinciding with the diameter of the work, said guide fingers being arranged to cooperate with said guide plate to maintain the work in single layer formation while upon said plate, means positively to position said guide fingers in operative relation to the face of said guide plate, and means bodily to remove said guide fingers from operative relation to said guide plate.

25. In a grinding apparatus, a work con- 130

- tainer, a rotary feed member provided with interrupted longitudinal teeth adapted to receive work from said container, fingers arranged in said interruptions adapted to determine the degree of projection of said teeth into the work mass and other fingers constituting continuations of the first mentioned fingers to effect the stripping of the work from said teeth.
- 10 26. In a grinding apparatus, a rotary drum having a series of forwardly inclined peripheral blades adapted to separate work from a mass and advance the same in single layer formation.
- 15 27. In a grinding apparatus, a rotary feed member having a series of forwardly inclined peripheral blades adapted to separate the work from a mass and advance the same in single layer formation, guide fingers adjustably arranged with respect to said blades to regulate the effective working depth of said blades.
- 20 28. In combination, a grinder and means to feed work elements to said grinder including spaced guide fingers, the guide fingers adjacent the work ends of the work elements being spaced closer than those farther removed from said work ends.
- 25 29. In combination, a grinder, means to feed work elements to said grinder including spaced guide fingers, the guide fingers adjacent the work ends of the work elements being spaced closer than those farther removed from said work ends, and means adjustably mounted adjacent to the ends of said blades to wipe superfluous work elements back into the mass.
- 30 30. In combination, a grinder, means to feed work elements to said grinder including spaced guide fingers, the guide fingers adjacent the work ends of the work elements being spaced closer than those farther removed from said work ends, and means adjustably mounted adjacent to the ends of said blades to wipe superfluous work elements back into the mass and to insure the formation of but a single layer of said elements upon said feed member.

In testimony whereof, I have signed my name to this specification.

JONATHAN A. HUNT.
